UNITED STATES PATENT OFFICE

2,238,508

CASH REGISTER

Theodor Schrimpf, Berlin-Neukolln, Germany,
assignor to The National Cash Register Company, Dayton, Ohio, a corporation of Maryland

Application April 17, 1936, Serial No. 74,842
In Germany April 24, 1935

16 Claims. (Cl. 235—6)

This invention relates to cash registers and accounting machines and particularly to that class having rows of interspersed totalizers of the type shown in the United States patent to Ernst Breitling, No. 1,899,455, granted February 28, 1933. In machines of the above type, when it is desired to select a totalizer from a row, the row of totalizers containing the totalizer to be selected is coupled with an engaging device during the operation of the machine, whereby the entire totalizer row and rider shaft are shifted transversely toward the totalizer actuating devices. Therefore, only those totalizer rows are moved toward the totalizer actuating devices that have a totalizer selected therefrom.

In connection with certain types of posting, it is highly desirable to record an identifying character representing the setting or selecting means for the selected totalizer, and at the same time prevent that particular totalizer from being engaged with the actuating devices.

It is therefore an object of this invention to provide machines of the above mentioned type with means for preventing a totalizer from being engaged with the actuating devices, notwithstanding the fact that the totalizer has been selected by the setting or selecting devices.

It is a further object of this invention to provide a machine of the above mentioned type having a plurality of rows of interspersed totalizers, with selecting means associated with each row in combination with a plurality of means located in the various rows of selecting means for preventing one or more of the selected totalizers from being engaged with their actuating means, depending upon the type of entry which is being made in the machine.

A still further object of this invention is to provide means to control the effectivity of the totalizer engaging means when the first mentioned means is moved into one of a plurality of positions of adjustment into which it is capable of being moved.

Another object of this invention is to provide a novel structure including a plurality of slides controlled by a plurality of depressible manipulative devices and by a manipulative lever, to determine which of the selected totalizers are to be engaged with the actuators.

With these and incidental objects in view, the invention includes certain novel features of construction and combinations of parts, the essential elements of which are set forth in appended claims, and a preferred form or embodiment of which is hereinafter described with reference to

the drawings which accompany and form part of this specification.

Of said drawings:

Fig. 1 is a cross section through the machine and the totalizer selecting devices.

Fig. 2 is a cross section through the machine and the totalizer engaging devices.

Fig. 3 is a detail of the cam device for preventing the engagement of a selected totalizer upon the depression of certain keys.

Fig. 4 is a cross section through the machine alongside one of the amount differential mechanisms.

Fig. 5 is a transverse section through the machine showing the totalizer selecting and engaging devices and the novel control mechanism for the engaging devices.

Fig. 6 is a diagrammatic view of the keyboard of an accounting machine embodying the present invention.

Fig. 7 is a top view of the control device for disabling the totalizer engaging means.

Fig. 8 is an enlarged detail view of some of the mechanism shown in the lower part of Fig. 5.

Fig. 9 is a detail perspective view of one train of a plurality of levers shown in the upper part of Fig. 2.

GENERAL DESCRIPTION

30 In the illustrated machine embodying this invention, there is provided a keyboard having eight rows of amount keys, three rows of totalizer selecting keys, a row of cashier's keys, and a control or mode of operation lever.

35 In the machine illustrated, and particularly in Figs. 2 and 4, there are four lines or rows of interspersed totalizers. For convenience in describing these totalizers in detail later on in the specification, they will be designated by the characters *a*, *b*, *c*, and *d*, and the reference numerals relating to these particular totalizers will carry the letters *a*, *b*, *c*, and *d*. Referring particularly to Fig. 4, the upper totalizer row is

40 designated *a*, the back row as *b*, the lower right-hand row as *c*, and the lower left-hand row as *d*. Referring now particularly to Fig. 6, the "Kind of tax" keys 1 to 8 and the "Refund" key 16 in this row control the selection of the totalizers 45 in row *a*. The "Refund" key in this line controls the disabling of the totalizer rows *b*, *c*, and *d*.

45 Referring now particularly to Fig. 6, the "Kind of tax" keys 9 to 16 and the "Refund" key 15 in this row controls the engagement of the totalizers in row *b*. This "Refund" 50

55 The "Kind of tax" keys 9 to 16 and the "Refund" key 15 in this row controls the engagement of the totalizers in row *b*. This "Refund"

DETAILED DESCRIPTION

Keyboard

key also controls the disabling of the totalizer rows *a*, *c*, and *d*.

The "Manner of payment" keys designated as "Cash," "Post office checking account," "Remittance by money order," and "Banks" keys; and also the two lower keys in this row of keys designated "Fees" and "Past due or interest" control the selection of the totalizers in row *c*. The "Fees" key and the "Past due or interest" key each control the disabling of the totalizer rows *a* and *b*.

The cashier's keys control the engagement of the totalizers in row *d*.

When the control or mode of operation lever *5* is moved into the "duplicating" position, it controls the disabling of all totalizer rows *a*, *b*, *c*, and *d*.

There is, of course, a differential mechanism associated with each of the banks of keys, which differential mechanism is of the general type disclosed in the above mentioned Breitling Patent No. 1,899,455.

The differential mechanism associated with the amount banks of keys controls the amounts to be entered into the various totalizers, as determined by the keys which are depressed for the various operations of the machine. The amount differentials and also the differentials associated with the totalizer selecting keys are what are known as the "scissors" type of differentials.

The totalizers in this machine are selected in a manner known in the art and shown in the Breitling patent, by a rider shaft shifted transversely of the totalizer wheels themselves and internally thereof.

This type of totalizer selection is associated with a coupling device which is automatically shifted with the selecting means, so that when a totalizer has been selected, its engagement with its actuator becomes automatic upon the operation of the machine.

However, in the present invention, devices are provided to control this coupling means, so that upon certain types of operations the totalizer will not be engaged with its actuators, notwithstanding the fact that it had been previously selected for engagement.

This particular means for so controlling the engaging of the selected totalizers is under the control of four keys and the control or mode of operation lever. One of the keys is arranged at the bottom of each row of the totalizer selecting keys *1* to *16*, which particular selecting keys, for the purpose of illustrating the invention, select totalizers which have been assigned to various kinds of taxes which are collectible. These two keys are, in this invention, designated "Refund" keys. The other two control keys for preventing the engagement of selected totalizers are located in the bottom of the row of control keys which are designated as "Manner of payment" keys, in which there is a "Cash" key, a "Post office checking account" key, a "Remittance by money order" key, and a "Banks" key. The two control keys in this row are marked "Fees" and "Past due or interest."

The control or mode of operation lever *5* has four positions of adjustment, namely, "adding," "reading," "resetting," and "duplicating." When moved into the "duplicating" position, all of the selected totalizers have their engaging mechanisms so controlled that none of the selected totalizers will be engaged.

For the purposes of illustration, the accounting machine embodying the present invention is assumed as being used in a tax office for recording various kinds of tax payments.

To this end, the machine is provided with a plurality of banks of amount keys *10* (Figs. 4 and 6), two banks of totalizer selecting keys *11* and *12*, which select totalizers to segregate the kinds of taxes being paid. Another bank of totalizer selecting keys *13* classifies the tax payments into four classifications, namely, cash, payments received, payments received by post office checking accounts, remittance by money order, and remittance through banks. Another row of totalizer selecting keys *14* represents the cashiers on duty at various times handling the transactions. These cashiers' keys are also what are known in the art as machine or motor releasing keys.

A control or mode of operation lever *5* is arranged at the right of the keyboard and is adapted to be moved into four positions of adjustment, namely, adding, reading, resetting, and duplicating.

For normal entries and registrations, it is necessary to depress a kind of tax key *11* or *12*, a manner of payment key *13*, and a cashier's key *14*, and also have the control lever *5* set in its adding position.

On certain occasions it may require that an amount which has been paid in for some sort of undue tax may have to be refunded to the taxpayer. Therefore, the machine is provided with two "Refund" keys *15* and *16*, one located at the bottom of each of the two rows of kinds of tax keys *11* and *12*. The "Refund" *15* key is to be used in connection with the selecting keys *11* and the "Refund" key *16* is to be used in connection with the selecting keys *12*.

The amount to be refunded is to be accumulated in, and retained only in, the two refunding totalizers associated with the keys *15* and *16*. It is desirable to make a printed record of the kind of tax which has been refunded, and therefore, if that kind of tax falls in the classification represented by the keys *11*, one of these keys is depressed and the refunding key *15* is depressed. The manner of paying the refund is classified by depressing one of the keys *13*, and then the cashier's key *14* is depressed to release the machine.

In such an operation the totalizer associated with the key *11*, even though selected, will not be engaged with the actuators, neither will the totalizer associated with the manner of payment key *13* be engaged, nor will the cashier's totalizer be engaged. It is the depression of the refunding key *15* which controls mechanisms to be later described, which mechanism, in turn, controls the totalizer engaging mechanism for the keys *11*, *13*, and *14*, so that any totalizer selected by those keys in the particular operation just mentioned will not be engaged with their actuators.

The ultimate result of such an operation is that the refunded amount will be entered only into the refund totalizer associated with the key *15*, but at the same time, a printed record is made of the kind of tax refunded, the manner of payment of the refund, and the cashier who received that payment.

A somewhat similar case occurs when fees or

interest for deferred payments are to be recorded. For such registrations, a key 17 or 18 is to be depressed, along with the corresponding key 11 or 12 and the cashier's key 14. The fees and interest on deferred, or past due, payments are to be accumulated on the totalizer associated with whichever of those keys is depressed, as well as on a cashier's totalizer.

In view of the fact that only the totalizer associated with the key 17 or 18 which has been depressed, and also the totalizer associated with the cashier's key which has been depressed, have been selected for operation, the depression of either of the keys 17 or 18 controls the totalizer rows *a* and *b* so that the totalizers selected by the depression of either of the keys 11 or 12 will not be engaged with the actuators.

In duplicating postings, it is desirable to have printed records of the data indicating the kind of tax paid, the manner of payment, and the cashier who received that payment. However, the amount of money set up on such duplicate postings is not to be accumulated in any of the totalizers selected by the depression of any of the keys 11 or 12, 13, and 14. Therefore, the mode of operation lever 5 has a separate or "duplicating" position into which it may be moved, and, when moved into this position, this lever controls novel mechanism to disable the totalizer engaging means associated with all four of the totalizer rows.

Normal totalizer selecting mechanism

To give a better understanding of the mechanism for controlling the disabling of the totalizer engaging mechanisms, the normal totalizer selecting and engaging mechanism will be described first.

By depressing one of the totalizer keys 11 to 18, the respective associated zero stop pawl 20 (Fig. 40 1) is lifted out of the path of the differential mechanism.

At the start of the machine operation, a rock shaft 21 (Figs. 1, 4, and 5) is given a partial rotation in a counterclockwise direction, whereby in each bank having a key depressed, through the medium of the differential devices 22' to 29' (Fig. 5) the two elements 30' and 31' of the totalizer selecting differential mechanism are advanced in a manner well known in the art to the 50 stems of the keys depressed at that time.

For example, the differential element 32' associated with the keys in the "Manner of payment" bank has its stud extending into the path of the two elements 30' and 31' and is embraced in scissors-like fashion between those elements and adjusted commensurate with the key depressed. The setting of the differential element 32' is transmitted to the respective cam groove roll 40c by the parts 33c to 39c (Figs. 1 and 5).

The cam groove of roll 40c (see also Fig. 8) is engaged by a roller 41c carried on an arm 42c pinned to a shaft 43c shiftable supported by frames 44 and 45. Referring to Figs. 5 and 8, it will be noticed that the left-hand end of the shaft 43c has secured thereto a plate 46c guided on a shaft 50c. This plate 46c, as shown in Fig. 1, has two slots. A rider shaft 51c which couples, in the manner described in the above mentioned Breitling patent, by means of its rider 52c (Figs. 5 and 8), the adding wheels 53c with the differential wheels 54c of each denominational order, and the shaft 55c, which locks the wheels 53c of the totalizers not selected, are unshiftably carried in the slots of the plate 46c. Correspond-

ing with the form of the groove of the cam roll 40c, the shaft 43c and the plate 46c are shifted to the left commensurate with the setting of the cam groove roll 40c, whereby the rider shaft 51c selects the respective totalizer of this row under control of the keys 13 or 17 or 18.

The plate 46c has secured thereto a guiding pin 56c (Figs. 5 and 8). A coupling pin 57c, shiftable supported by two arms 81c and 82c connected by a sleeve 80c, is in axial alignment with the pin 56c. The coupling pin 57c is connected to the arm 42c by means of two set collars 79c, so that the coupling pin 57c is urged to take part in the movement of the shaft 43c when the same is shifted, just as does the guiding pin 56c. But this shifting movement of the coupling pin 57c is not transmitted to the arms 81c and 82c because the coupling pin shifts in the bearings of said arms.

The arm 82c has a hub 83c engaging an enlarged portion of a slot 61c (Fig. 2) of a totalizer engaging lever 60c pivoted on the shaft 50c. The lever 60c also has two rollers 62c cooperating with a cam disk 63c connected to a gear 64c (Figs. 2, 5, and 8) meshing with a gear 65c fast on a shaft 66. The shaft 66 also has secured thereto a gear 67 meshing with the unmutilated set of teeth of a pinion rotatable on the rock shaft 21. This pinion is adapted to be shifted in a manner well known, by the mode of operation lever 5 whereby, according to the position in which the lever 5 is set, its unmutilated set of teeth 68 faces a certain gear segment of a toothed drum 74, and the locking teeth 69 cooperate with either the locking disk 71 for "adding," or the disk 72 for "reading," or the disk 73 for "resetting." When the lever 5 is moved from "adding" to "duplicating" position, the pinion 68, 69 is not shifted.

The teeth of the drum 74 and the locking disks 71, 72, and 73, all secured to the middle shaft 75, are so formed that when the shaft 75 is driven, the pinion 68, 69 is given two quarter-rotations at the times corresponding with the different modes of operation. By means of the gearing 67, 66, 65c, and 64c, these two quarter-rotations are transmitted in such a way to the cam disk 63c as to give it two half-rotations. These two half-rotations of the disk 63c rock the lever 60c and, in connection therewith, the arms 81c and 82c first counter-clockwise (Fig. 2) and then return the same to their normal positions. Since the gear 65c is also in driving connection with the gears 65d, 65b, and 65a, the cam disks 63d, 63b, and 63a for the three other totalizer rows *d*, *b*, and *a* are actuated in the same way.

The coupling pin 57c supported by the arms 81c and 82c is carried along at this time, this movement being permitted by a slot 77c (Fig. 1) in the arm 42c. If no totalizer in this row *c* has been selected, that is, if the shaft 43c and the coupling pin 57c are in their right-hand positions as viewed in Fig. 5, the rocking movement of the lever 60c and arms 81c and 82c has no effect on the totalizer row. If, however, the cam 40c is rotated commensurate with the totalizer selecting key depressed at that time, in the row of keys "Manner of payment," such rotation of the cam 40c shifts the shaft 43c to the left, as viewed in Figs. 5 and 8, whereupon the coupling pin 57c enters the bore of an arm 85c occupied up to that time by the pin 56c of the plate 46c.

This arm 85c is fast on the shaft 50c which carries the totalizer frame 86c. Therefore, after 75 the selection of the totalizer has been effected,

the lever 60c, during the first half-rotation of the cam disk 63c, is coupled by the pin 57c with the arm 85c, and therefore the shaft 50c with the totalizer frame 86c is rocked to bring the actuating wheels 54c into mesh with gears 87c connected through the intermediate wheels 89c, 28, and 29 to the main differential elements 30 of amount differential devices (Fig. 4). When the main differential elements 30 associated with the amount keys return from their set positions into their rest positions, the adding wheels 53c, coupled with the actuating wheels 54c of the totalizer selected at that time, are advanced a number of steps commensurate with the value of the amount set up. After this accumulating takes place, the engaged totalizer row is disengaged during the second half-rotation of the cam disk 60c.

There is a totalizer engaging and disengaging mechanism associated with each of the totalizer rows *a*, *b*, and *d*, and, as they are identical with the mechanisms just described in connection with totalizer row *c*, no further description will be given. However, like parts of these mechanisms are referred to by the same reference numerals and distinguished by the letters *a*, *b*, and *d* following those numerals.

Totalizer engaging controlling, or disabling mechanism

To prevent, in certain cases, a selected totalizer from being engaged, according to this invention, the coupling of the totalizer engaging lever 60c and the arm 82c must be prevented. To this end, the sleeve 80c and its two arms 81c and 82c are moved to the right in a manner to be hereinafter described (Figs. 5 and 8), whereby the hub 83c, serving as a bearing in the lever 60c for the coupling pin 57c, is moved out of the enlarged portion of the slot 61c of the lever 60c (Fig. 2). With the hub 83c disconnected from the lever 60c, when this lever 60c is given its uniform rocking movement, the slot wall 61c rides ineffectively on the coupling pin 57c.

Secured to the sleeve 80c is a guide roller 90c (Figs. 2, 3, and 5) engaging the cam groove of a cam plate 91c. The plate 91c is secured to an arcuate slide 93c by means of an angular piece 92c, the slide being guided on stationary pins 94. These slides are numbered 93a, 93b, 93c, and 93d, one being associated with each of its respective totalizer rows *a*, *b*, *c*, and *d*. A link 95c (see also Fig. 9) joins the upper end of the slide 93c with a lever 96c pivoted on a cross rod 97. A pin 98c of the lever 96c is embraced by the forked end of a second lever 99c rotatably mounted on a sleeve 102 on a shaft 100. The cross rod 97 is supported by two arms 101 connected by the sleeve 102 (Fig. 5) to a third arm 103, having connected thereto a pitman 104 guided on the shaft 75 and carrying a roller 105 engaging the cam groove of a disk 106 fast on the shaft 75. By means of this cam disk 106 the two arms 101 carrying the rod 97 are given a clockwise rotation (Fig. 2) shortly after the start of the operation of the machine. They are returned counterclockwise to normal position shortly before the end of the operation of the machine.

There is a link 95, lever 96, pin 98, and lever 99 associated with each of the totalizer rows *a*, *b*, *c*, and *d*, and these parts carry the designating letters *a*, *b*, *c*, and *d* after their reference numbers.

Each of the four levers 99a to 99d has allotted thereto a control slide 108a to 108d, all slides being shiftable on the stationary shaft 100. Each of the control slides 108a to 108d has an associated

integral projection 110a to 110d (Fig. 7) normally lying outside of the path of its respective associated lever 99a to 99d. The control slides 108a to 108d are held in their normal positions by springs 111a to 111d. The four control slides 108a to 108d have four holes 112a to 112d, 113a to 113d, 114a to 114d, and 115a to 115d. All these holes lie above one another and are engaged by pins 117, 118, 119, and 120 respectively, as shown in Figs. 2, 5, and 7. These pins 117, 118, 119, and 120 are secured to bent-over portions of pitmans 122, 123, 124, and 125 respectively, each being guided on the shaft 100 and connected to slides 127, 128, 129, and 130 respectively.

13 The slide 127 is associated with the keys 11 and 16, the slide 128 is associated with the keys 12 and 15, and the slide 129 is associated with the keys 13, 17, and 18. These slides are located adjacent their respective keys and are provided with sloping projections cooperating with the keys 16, 15, 17, and 18. The slide 127 cooperates with the key 16, the slide 128 cooperates with the key 15, and the slide 129 cooperates with the keys 17 and 18 (Fig. 1). These slides are moved upwardly by the cooperation of the pins of the keys depressed with the sloping projections on the slides.

As previously stated, when the "Refunding" key 16 is depressed, the totalizers of the rows *b*, *c* and *d* are not to be engaged with the actuators. To this end, the recesses 112a to 112d of the four control slides 108a to 108d are so formed that when the pin 117 is moved toward the back of the machine upon depression of the key 16, the control slides 108b, 108c, and 108d are shifted to the left, and the control slide 108a remains in its right-hand position. With the slides in these positions, the projections 110b, 110c, and 110d are moved into the paths of the upper ends of the levers 99b, 99c, and 99d respectively, while the projection 110a remains out of the path of the upper end of the lever 99a.

Therefore, as the pitman 104 rocks the arms 101 clockwise, due to the fact that the levers 99b, 99c, and 99d cannot move, the rod 97 rocks the levers 98b, 98c, and 98d clockwise with their pins 98b, 98c, and 98d as the fulcrum, thus moving the respective links 95b, 95c, and 95d to the left as viewed in Fig. 2, whereupon the associated slides 93b, 93c, and 93d are moved, and their integral cam plates 91b, 91c, and 91d, through their cooperating rollers 90b, 90c, and 90d, shift their associated arms 82b, 82c, and 82d to the right as viewed in Fig. 5 with respect to arm 85, thus disengaging the hubs 83b, 83c, and 83d from the levers 60b, 60c, and 60d.

Therefore, notwithstanding the fact that a totalizer had been selected in each of the totalizer rows *b*, *c*, and *d* by the depression of a key 12, 13, and 14 respectively, these totalizer rows will not be rocked to engage the selected totalizer with the actuator, due to the engagement of the hubs 83b, 83c, and 83d from the totalizer engaging levers 60b, 60c, and 60d. Thus, only the totalizer line *a* will be rocked to engage the selected totalizer of that line, in this case the totalizer associated with the "Refund" key 16, with the actuators.

By depressing the "Refunding" key 15, the control slides 108a, 108c, and 108d are moved into effective positions whereby the totalizer rows *a*, *c*, and *d*, through the disengagement of their associated hubs 83a, 83c, and 83d from their engaging levers 60a, 60c, and 60d, effected in the same manner as described above in connection with totalizer row *a*, are not engaged with the actuators.

However, the totalizer row *b* will be rocked into engagement, so that the selected totalizer, in this case the totalizer associated with the "Refund" key *15*, may be actuated.

Upon depression of either one of the keys *17* or *18*, the control slides *108a* and *108b* are moved to the left, whereby their associated hubs *83a* and *83b* are disengaged from the totalizer engaging levers *60a* and *60b* respectively, whereupon the totalizer rows *a* and *b*, associated with the "Kind of tax" keys *11* and *12*, will not be engaged with the actuators. However, the totalizer rows *c* and *d*, the latter being associated with the cashier's keys *14* and the former associated with the keys *17* and *18*, will be engaged with their actuators, whereby the totalizer selected, in row *c* by either the key *17* or *18*, and in row *d* by one of the keys *14*, to have accumulated therein the amount set up on the keyboard.

When the mode of operation lever *5* is moved into the "duplicating" position, its pin *132* (Figs. 2 and 5) strikes a lug *133* of the slide *130* and carries it along against the action of its spring, whereby the pitman *125* is moved to the right and its pin *120*, due to the forms of the recesses *115a* to *115d*, moves all of the control slides *108a* to *108d* to the left as viewed in Figs. 5 and 7, thus moving all of the projections *110a* to *110d* in the paths of the levers *99a* to *99d*, so that all of the hubs *83a* to *83d* will be disengaged from their respective levers *60a* to *60d*, so that upon movement of the cams *63a* to *63d* none of the totalizer rows will be engaged with the actuators during a duplicating operation.

Referring to Figs. 5 and 8, when the hub *83c* is disengaged from the lever *60c*, a pin *135c* on the arm *81c* enters a hole *136c* in the frame *44*, thus maintaining the arms *60c* and *82c* in proper alignment, so that when the pitman *104* returns the arms *101* and levers *96c* to normal position, the hub *83c* can be properly engaged with its lever *60c* by the slide *93c* and cam *91c*.

There is a pin *135* on each of the arms *81a*, *81b*, and *81d* and also a hole *136* for each pin.

OPERATION

In posting an amount refunded, let us assume that one of the "Kind of tax" keys *12*, the "Cash" key *13*, and one of the cashier's keys *14* is depressed, along with the "Refunding" key *16*. By 50 depressing the "Refunding" key *16*, the slide *127* and pitman *122* are moved upwardly. When this occurs, the control slides *108b*, *108c*, and *108d* are moved to the left by the pin *117* (Fig. 7), and the projections *110b*, *110c*, and *110d* are moved into the paths of the levers *99b*, *99c*, and *99d*. Shortly after the start of the operation, the cam *106* moves the arms *101* clockwise. In this case, the arms *96b*, *96c*, and *96d* are rocked clockwise with their pins *98b*, *98c*, and *98d* as the fulcrum, thus drawing the links *95b*, *95c*, and *95d* rearwardly to move the slides *93b*, *93c*, and *93d*, whereupon their cams disengage the hubs *83b*, *83c*, and *83d* from the levers *60b*, *60c*, and *60d*, thus preventing the engagement of the totalizer rows *b*, *c*, and *d* with the actuators.

During such an operation, due to the fact that the slide *108a* is not moved by the pin *117*, the projection *110a* does not move into the path of the lever *99a*, and, consequently, when the arms *101* are rocked clockwise by the cam *106*, the rod *97* rocks the lever *96a* counter-clockwise with its stud *107a* as the pivot point and the lever *99a*, through the pin *98a*, is rocked clockwise. The fact that this lever *99a* is rocked clockwise per-

mits the counter-clockwise movement of the lever *96a* around its stud *107*, and, consequently, the associated link *95* and slide *93a* are not moved. Therefore, the hub *83a* is not disengaged from the lever *60a*, and the totalizer row *a* is rocked into engagement with the actuators, whereupon the selected totalizer, in this case the totalizer associated with the "Refund" key *16*, is engaged with the actuator to have accumulated therein the amount of tax refunded.

Also, in this operation, the arms *81b*, *81c*, and *81d*, which have their associated hubs *83b*, *83c*, and *83d* disengaged from the totalizer engaging levers *60b*, *60c*, and *60d*, are locked in their disengaged positions, to the right of that shown in Fig. 5, by their pins *135b*, *135c*, and *135d* having entered the holes *136b*, *136c*, and *136d* in the side frame *44*, thus preventing any movement of the arms *81b*, *81c*, and *81d* and *82b*, *82c*, and *82d*, and maintaining them in proper alignment at all times while they are in disengaged positions.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the class described, the combination of a plurality of groups of totalizers; a support for each group of totalizers; a plurality of totalizer engaging means, one for each group of totalizers operable at each operation of the machine; a means normally coupled to each of the engaging means but normally uncoupled from the totalizer supports; a plurality of means, one associated with each group of totalizers and longitudinally shiftable to select the totalizer in its related group and simultaneously couple the supports for the related totalizer group with the means normally coupled to the engaging means; a plurality of manipulative means; and means operable under control of the manipulative means to uncouple two or more of the normally coupled means from the engaging means to render the totalizer engaging means for two or more groups of totalizers ineffective.

2. In a machine of the class described, the combination of a plurality of groups of totalizers; a separate totalizer engaging means for each row of totalizers; a plurality of devices, one device normally connected to each of the totalizer engaging means; a slidable coupling member carried by each device; a plurality of means, one means to select totalizers in each group; a plurality of operating members, one operating member common to each selecting means and slidable coupling member to simultaneously actuate the related selecting member and coupling member to couple the devices to the related groups of totalizers so that the engaging means can engage the selected totalizers; manipulative control members to control the totalizer selecting means; means to shift each of the devices relatively to the engaging means and slidable coupling members to disconnect the devices from the engaging means; and selecting means settable under control of the manipulative control members to determine which of the means to shift the devices is to be operated to shift one or more of the devices to determine which totalizers are to be disconnected from the engaging means.

3. In a machine of the class described, the

combination of a plurality of groups of totalizers; a separate totalizer engaging means for each group of totalizers; a plurality of devices, one device normally connected to each of the totalizer engaging means; a slideable coupling member carried by each device; a plurality of means, one means to select totalizers in each group; a plurality of operating members, one operating member common to each selecting means and coupling member to simultaneously actuate the related selecting member and coupling member to select related totalizers and to couple the devices to the related group of totalizers so that the engaging means can engage the selected totalizers; manipulative control members to control the extent of actuation of the common operating members; a cam connected to each device to determine the position of the devices; selecting elements positioned by the manipulative members; and connections to the cams, said connections selectively operated according to the positions of the elements after the elements are set by the manipulative devices to operate one or more of the cams to move the devices connected to the selected cams out of normal position wherein the devices are disconnected from the engaging means and the corresponding totalizers are not engaged, notwithstanding the selection of said totalizers.

4. In a machine of the class described, the combination of a plurality of groups of totalizers; totalizer engaging means; shiftable supports normally coupled with the engaging means but normally uncoupled from the groups of totalizers; coupling means supported by the shiftable supports and operable to connect the groups of totalizers with the shiftable supports; means for selecting totalizers from the groups and for operating the coupling means; a plurality of members having cams to shift said supports and thereby uncouple the support from the engaging means to render the engaging means ineffective upon operation of said members; common means to operate said members; and selectable means to determine which of said members shall be operated by said common operating means.

5. In a machine of the class described having a plurality of groups of totalizers, engaging means for each group, a member normally connected with each engaging means, and totalizer selecting means, in combination with shiftable coupling means for each group operable upon the selection of a totalizer in its group to couple the selected group with the member normally connected with the engaging means, the coupling means being supported by said member; a plurality of cam members adapted to move said members to disconnect the members from the engaging means to render the engaging means ineffective upon operation of said cam members; a lever associated with each cam member to actuate the cam member; a common operating means for all levers; a plurality of control slides; means on the control slides adapted to be moved into the paths of the levers to render their operation effective to operate the cam members; and a plurality of manipulative means to operate the control slides.

6. In a machine of the class described, the combination of a totalizer; a support for the totalizer; actuators for the totalizer; means to 70 actuate said support to engage the totalizer with the actuators, said means being normally uncoupled from the totalizer support; a shiftable element normally connected with the engaging means; means supported by the shiftable ele-

75 ment and movable thereon to couple the shiftable element with the totalizer support; means to shift the shiftable element to disengage the shiftable element from the engaging means; and manipulative devices to control the shifting of the shiftable member.

7. In a machine of the class described, the combination of a plurality of groups of totalizers; actuators therefor; a support for each group of totalizers; a totalizer engaging means for each group of totalizers and operable at each operation of the machine; a shiftable means normally in driving connection with each of the engaging means; means associated with each group of totalizers and longitudinally adjustable to select totalizers in the groups; means connected to said selecting means and settable into position by said selecting means to couple each shiftable means with a corresponding totalizer support so that the shiftable means may operate the supports when the shiftable means are operated by the engaging means; a plurality of manipulative means; and means operable under control of the manipulative means to shift the shiftable means out of driving connection with the engaging means to render the engaging means ineffective to engage the totalizers with the actuators, notwithstanding the selection of a totalizer in such groups and the coupling of the shiftable means to the supporting means.

8. In a machine of the class described, the combination of a plurality of groups of totalizers; a support for each group of totalizers; a plurality of totalizer engaging means, one for each group of totalizers and operable at each operation of the machine; a plurality of means, one connected to each of the totalizer engaging means but normally uncoupled from its related totalizer support; a plurality of means, one associated with each row of totalizers and longitudinally shiftable to select a totalizer in its related group and to simultaneously couple its related support with the means connected to the totalizer engaging means; a control lever; and means operated under control of the lever to adjust the plurality of means connected to the totalizer engaging means to disconnect them from the totalizer engaging means for rendering the totalizer engaging means for all of said rows of totalizers ineffective, notwithstanding the selection of a totalizer in such rows and the simultaneous coupling of the totalizer group supports to their related means connected to the engaging means.

9. In a machine of the class described, the combination of a totalizer; actuators therefor; a support for the totalizer; totalizer engaging means operable at each operation of the machine; shiftable means normally in driving engagement with said engaging means; means settable into a position to couple the shiftable means to the support so that the shiftable means may operate the support, when the shiftable means is operated by the engaging means, to cause the totalizer to be engaged with the actuators; manipulative means; and means operable under control of the manipulative means to shift said shiftable means out of driving engagement with said engaging means to prevent the engagement of the totalizer with the actuators even though the coupling means is in said coupling position with respect to the totalizer support and the shiftable means.

10. In a machine of the class described, the combination of a plurality of groups of totalizers; means, including a totalizer engaging element and a shiftable means normally coupled together

but adapted to be uncoupled, for each group of totalizers, said engaging elements being operable at each operation of the machine; means for selecting a totalizer from each group and for automatically coupling the groups with their engaging elements and shiftable means; a plurality of shiftable slides; a projection on each slide; a lever associated with each projection, said projections being in the path of the levers when the slides are in one position and out of the path of the levers when the slides are in another position; connections between the levers and said shiftable means; means to move the levers into cooperating relationship with the projections to actuate the connections to thereby move the said shiftable means to uncouple the shiftable means from the engaging element; and a plurality of manipulative devices for shifting a varying number of said slides depending upon which one of said manipulative devices is operated.

11. In a machine of the class described, the combination of a plurality of groups of totalizers; a totalizer engaging means for each group of totalizers; a shiftable element for each group of totalizers, said totalizer engaging means and shiftable element being normally coupled together but normally uncoupled from the groups of totalizers; coupling means operable to connect the groups of totalizers with said engaging means and shiftable elements; means for selecting totalizers from the groups and for operating the coupling means; a plurality of members having cams to shift said shiftable elements to disconnect the shiftable elements from the engaging means to render the engaging means ineffective upon operation of said members; common means to operate said members; a plurality of manipulative devices; a plurality of control slides settable under control of said manipulative devices; and means on said control slides to determine which of said members shall be operated by said common operating means.

12. In a machine of the class described, the combination of a plurality of groups of totalizers; a totalizer engaging means for each group of totalizers; a shiftable element for each group of totalizers, said totalizer engaging means and shiftable elements being normally connected together for common movement; coupling means operable to connect the groups of totalizers with said shiftable element and engaging means; means for selecting totalizers from the groups and for operating the coupling means to couple the said shiftable element and engaging means to the associated group of totalizers; a plurality of cam members adapted to shift said shiftable elements to disconnect the shiftable elements from the engaging means to render the engaging means ineffective upon operation of said cam members; a lever associated with each of said cam members and adapted to actuate the same, said levers capable of rotation about either end, rotation about one end effecting an actuation of said cam members, rotation about the other end being ineffective to actuate said cam members; a plurality of manipulative devices; a plurality of adjustable control slides; means on the control slides to cause a certain type of movement of the levers when the slides are in certain positions; means to operate the levers; and means intermediate said devices and said control slides to selectively adjust said control slides depending upon which of said manipulative devices is operated.

13. In a machine of the class described, the combination of a totalizer; actuators therefor; a totalizer support; means including a plurality of interconnected and relatively adjustable elements normally uncoupled from the totalizer support; means operable to adjust one of said elements of the plurality of elements to couple the plurality of elements to the totalizer support; actuating means for the plurality of elements and the totalizer support to move the totalizer into mesh with the actuators when the plurality of elements are coupled to the totalizer support; means operable to adjust a second one of said elements to disconnect said second element of the plurality of elements from a third element of said plurality of elements to prevent the totalizer from being moved into mesh with the actuators even though the actuating means operates one of the elements and the said one element has been operated to couple the plurality of elements to the totalizer; manipulative control devices; a control member settable under control of the manipulative devices; control surfaces on the control member; and feelers connected with the last-named means and coacting with the control surfaces to control the operation of the last-named means.

14. In a machine of the class described having a plurality of groups of totalizers, an engaging means for each group, means normally connected to each engaging means to move in unison therewith, and totalizer selecting means associated with each engaging means, in combination with shiftable coupling means for each group of totalizers operable upon the selection of a totalizer in its associated group to connect its group with the associated engaging means and the means normally connected therewith; a plurality of cam members, each cam member operable to control the movement of a related one of said means connected to the engaging means, to disconnect the engaging means from its associated means normally connected thereto, to render the associated engaging means ineffective; a plurality of elements adapted to control the operation of said cam members to determine which one of the means connected to the engaging means shall be moved to render its associated engaging means ineffective; means to operate the plurality of cam members; and a plurality of manipulative devices for actuating said elements.

15. In a machine of the class described, the combination of a totalizer; actuators therefor; a support for the totalizer; means including a plurality of interconnected and relatively adjustable elements normally disconnected from the totalizer support; means operable to move a first one of said elements into engagement with the totalizer support to connect the plurality of elements to the totalizer support; means coacting with a second one of the elements to actuate the plurality of interconnected elements and therethrough cause the totalizer to be meshed with the actuators when all the elements are connected together and to the totalizer support; and means connected to a third one of said elements, the last-named means being operable to disconnect said third element from the second one of said elements to disable the interconnection of the plurality of elements to thereby prevent the totalizer from being meshed with the actuators even though said first element has been moved into engagement with the totalizer support to connect the plurality of elements to the

totalizer support and the second element is actuated by its actuating means.

16. In a machine of the class described, the combination of a totalizer; actuators therefor; a support for the totalizer; means including three interconnected and relatively adjustable elements normally disconnected from the totalizer support; means to operate a first of said three elements; means to move a second element of said three elements to connect the second element with the totalizer support to couple the three interconnected elements to the totalizer support so that the totalizer can be engaged with the actuators when said first element is operated by its operating means; means con-

necting to a third element of said three elements and operable to adjust the third element relative to the other elements to disconnect the said third element from the first element to interrupt the interconnection between the three elements to thereby prevent the totalizer from being engaged with the actuators when the first element is operated and the second element is in said coupling position; normally ineffective operating means for the last-named means; and manipulative control devices to selectively render the operating means effective during certain machine operations.

THEODOR SCHRIMPFF.
